United States Patent Office

Des. 209,353

Patented Nov. 21, 1967

209,353

HELICOPTER

Buford J. Schramm, 115 N. Primrose,
Alhambra, Calif. 91801

Filed Mar. 25, 1966, Ser. No. 1,635

Term of patent 14 years

(Cl. D71—1)

FIG. 1 is a side elevation;

FIG. 2 is a front elevation;

FIG. 3 is a top plan view; and

FIG. 4 is a perspective view looking into the front left segment of the helicopter shown in FIGS. 1-3.

One of the rotor blades in FIG. 3 is fragmented for convenience of illustration.

I claim:

The ornamental design for a helicopter, as shown and described.
